UNITED STATES PATENT OFFICE.

JOHN A. MARTIN, OF IDABEL, OKLAHOMA, ASSIGNOR OF ONE-HALF TO R. K. BLACK,
OF IDABEL, OKLAHOMA.

PLOW ATTACHMENT.

1,183,999.

Specification of Letters Patent. Patented May 23, 1916.

Application filed February 10, 1916. Serial No. 77,483.

To all whom it may concern:

Be it known that I, JOHN A. MARTIN, a citizen of the United States, residing at Idabel, in the county of McCurtain and State of Oklahoma, have invented a new and useful Plow Attachment, of which the following is a specification.

This invention relates to cultivators and like agricultural implements, one of the objects of the invention being to provide means whereby a soil device of any desired construction such as a plow, colter, or the like, may be adjustably connected to a beam so as to be held at different angles relative thereto, the connecting means being such as to permit quick and accurate adjustment, insure stability and enable the beam to be used in connection with various kinds of soil engaging devices.

With the foregoing and other objects in view which will appear as the description proceeds, the invention resides in the combination and arrangement of parts and in the details of construction hereinafter described and claimed, it being understood that changes in the precise embodiment of the invention heretofore disclosed, can be made within the scope of what is claimed, without departing from the spirit of the invention.

In the accompanying drawings the preferred form of the invention has been shown.

In said drawings:—Figure 1 is a side elevation of a harrow embodying the present improvements. Fig. 2 is a plan view thereof. Fig. 3 is an enlarged section on line A—B Fig. 2. Fig. 4 is a section on line C—D Fig. 1, the standard being shown in elevation. Fig. 5 is an enlarged transverse section through a portion of the harrow, said section being taken on the line E—F Fig. 2.

Referring to the figures by characters of reference 1 designates a beam having handles connected to one end thereof. Formed within the rear portion of the beam is a slot 3 extending entirely through the beam from the top to the bottom thereof, the rear wall of the slot being concaved from top to bottom as shown at 4, while the front wall thereof is preferably straight as shown at 5 and merges into a supporting lip or flange 6 extending rearwardly at the bottom of the slot. The slot 3 is designed to receive a block 7 one end of which is rounded, as shown at 8 so as to fit snugly against the concaved wall 4. The other end is likewise

rounded, as shown at 9 and is adapted to engage the flange 6 and the front wall 5 of the slot.

Extending through the block 7 from top to bottom thereof is an opening 10 and this opening is designed to receive a standard 11. This standard can be one of several kinds. For example, and as shown in Fig. 1, it can be provided, at its lower end with a fork 12 in which a wheel 13 is journaled or, if preferred, a plow can be connected to the standard. In order to prevent the standard from shifting upwardly within the block, a block 14 is extended therearound and bears upwardly against the beam 1, this block being attached to the standard by means of a set screw 15. Said block, in the present instance, has a rearwardly extending tongue 16 on which is secured the front end of a spring 17 which curves downwardly and forwardly and is provided with a harrow or cultivator blade 18. Obviously movement upwardly of the standard relative to the beam 1 will be limited by the block 14. However, by loosening the set screw 15 standard 11 can be adjusted longitudinally and then by tightening the set screw the standard will be held against upward movement after such adjustment.

In the structure shown the harrow has been combined with the beam 1 and the standard 11. This harrow consists of pairs of arms 19 extended in opposite directions from the beam. The front arms of each pair are pivotally connected to the beam by a bolt 20 extending through the beam while the rear arms 19 are connected to the beam by a bolt 21 extending therethrough. Connected to the rear arms 19 are studs 22 extending upwardly from sleeves 23, the studs being screw threaded so as to hold the sleeves close to the arms 19. Extending through these sleeves are parallel spring strips 24 the rear ends of which are curved downwardly and forwardly and provided with soil engaging devices 25. The front ends of the spring strips are connected to the front ends of the arms 19 by pivot bolts 26. The outer ends of the arms 19 are connected to side links 27 which co-operate with beam 1 to form parallelograms.

Secured to each of the front arms 19 close to the sides of the beam 1 are holding strips 28 each of which is provided, in its front end portion, with a longitudinal series of

openings 29. A bolt 30 is extended transversely through the beam 1 and is adapted to extend through any one of the openings 29 in each of the strips 28. Thus it will be seen that by removing bolt 30 the strip 28 can be adjusted longitudinally, thus to swing the arms 19 outwardly or inwardly relative to the beam 1 and to correspondingly shift the strips 24 away from or toward each other. After the bolt 30 has been inserted through the strips 28 and secured, the arms 19 will be held securely against movement relatively to the beam 1.

By providing the particular connection 15 between the standard 11 and the beam 1, the said standard can be adjusted angularly by shifting the block 7 within the slot 3. After such shifting the block can be held by means of a set screw 31 inserted into 20 one side of the beam and engaging one side of the block as shown in Figs. 1 and 2.

Obviously blocks having openings of different sizes can be placed in the slot 3 for the purpose of accommodating different sizes 25 of standards 11. In any event pressure will be transmitted directly from the standard to the block and from the block against the concave wall 4 of the slot so that there are no bolts likely to become broken or 30 twisted as a result of excessive pressure. Instead the pressure is transmitted directly from the standard to the beam.

What is claimed is:—

1. In an implement of the class described, a beam having a slot extending therethrough from top to bottom thereof, a block adjustably mounted in the slot and bearing rearwardly against the rear wall thereof, means for holding the block against angular adjustment, a standard extending through and movable with the block, and a soil engaging device carried by the standard. 35

2. An agricultural implement including a beam having a slot extending therethrough from top to bottom thereof, a block seated in the slot, a flange normally supporting one end of the block, said slot having a concave wall for the reception of one end of the block, means for holding the block against movement upwardly and downwardly relative to the beam, a standard extending through the block and adjustable longitudinally therein, means carried by the standard and coöperating with the beam for limiting the upward movement of the standard relative to the block, and a soil engaging device carried by the standard. 45

In testimony that I claim the foregoing as my own, I have hereto affixed my signature in the presence of two witnesses.

JOHN A. MARTIN.
